(57) **CLAIM**

The ornamental design for a table base, as shown and described.

DESCRIPTION

FIG. 1 is a perspective view of the large dining table base of my design;

FIG. 2 is a top view of the large dining table base (the bottom view, being a mirror image of the top view, is not shown);

FIG. 3 is a front view of the large dining table base (the back view, being a mirror image of the front view, is not shown); and,

FIG. 4 is a right side view of the large dining table base (the left side view, being a minor image of the right side view, is not shown).
